UNITED STATES PATENT OFFICE.

MICHAEL MULDOON, OF LOUISVILLE, KENTUCKY.

DESIGN FOR MONUMENTAL STATUARY.

SPECIFICATION forming part of Design No. 13,727, dated March 13, 1883.

Application filed December 19, 1882. Term of patent 7 years.

To all whom it may concern:

Be it known that I, MICHAEL MULDOON, a citizen of the United States, residing at Louisville, in the county of Jefferson and State of Kentucky, have invented and produced a new and original Design for Monumental Statuary, of which the following is a specification, reference being had to the accompanying drawing, forming part thereof.

10 The drawing is a front elevation of the statue, showing its peculiar construction and ornamental designs.

15 The leading features of this my design for improvement in monumental statuary, entitled the "Angel of Memory," consist, first, in a foundation-base, upon which rests the base or lower part of the monument, from which arises the die-block, embellished with the representation of flowers hung in festoons carved thereon, and upon this last-named die-block rests a heavy shaft, not tall, but massive, and on each side of which stands a classic urn, on one side of which hangs a festoon of flowers, and on the other a heavy drapery with fringe on 20 the edges. The last-named shaft is provided with a cap ornamented with renaissance decorations, the whole work being surmounted by a colossal statue of the Angel of Memory, with its right arm reaching forward in the act of 25 strewing flowers on the grave below. This angel is represented as just alighting upon a bed of tropical plants and flowers in her robe, which is held in her left hand, in which she carries a quantity of flowers. The face of the 30 figure is covered by a thin veil, through which can be seen the Grecian features with their chaste expression. The extended wings of the figure are so carved that the feathers represented appear as real.

In the drawing, A A represent the foundation-base, which is made in form as shown in the drawing. B is the base or lower part of the monument, and is ornamented in front, as shown. C is the die-block, which is embellished by the representation of flowers in festoons. D is a massive shaft resting upon the die-block C, and is ornamented as shown. E E are classic urns, one on each side of the shaft D, and ornamented by festoons of flowers and a heavy drapery, F, with fringes. 45 The last-named shaft D is provided with a cap, G, ornamented with renaissance decorations H, the whole being surmounted by a colossal statue of the Angel of Memory, J, with her right arm reaching forward in the act of strewing flowers on the grave below. This angel J is represented as just alighting upon a bed of tropical plants and flowers, K, holding her robe and a quantity of flowers in her left hand L. N N are the extended wings, which are 50 ornamented by carving representing the feathers. Therefore,

I claim as my invention—

The monumental design or statue of the Angel of Memory herein shown and described, 55 the same consisting of the foundation-base A A and lower part of the monument, B, and die-block C, with its urn E E, drapery F, and shaft D, with its cap G, ornamental flowers H, and angel J, with her robes and flowers L, arm 60 K, and wings N N, substantially as herein described.

MICHAEL MULDOON.
